UNITED STATES PATENT OFFICE

145,810

DESIGN FOR A GRILL

Morgan J. Lewis, Philadelphia, Pa.

Application November 27, 1945, Serial No. 124,116

Term of patent 14 years

(Cl. D44—1)

To all whom it may concern:

Be it known that I, Morgan J. Lewis, a citizen of the United States, residing at 1510 West Hilton Street, Philadelphia, in the county of Philadelphia and Commonwealth of Pennsylvania, have invented a new, original, and ornamental Design for a Grill, of which the following is a specification, reference being had to the accompanying drawings, forming part thereof.

Figure 1 is a top plan view of a grill showing my new design.

Figure 2 is a section of Figure 1 on the line 2—2.

Figure 3 is a bottom plan view of the grill, showing the ornamental center spot and rings.

Figure 4 is a fragmentary section of Figure 1 on the line 4—4 of Figure 1, through the well.

Figure 5 is an enlarged broken section on the line 5—5 of Figure 1 showing the eccentricity of the annular channel, which is narrow on the side opposite to the well and widens as it approaches the junction with the well.

I claim:

The ornamental design for a grill, as shown.

MORGAN J. LEWIS.
